UNITED STATES PATENT OFFICE

2,523,167

PHASE CONTROL SYSTEM

Gustav E. Undy, Detroit, Mich., assignor to Weltronic Company, Detroit, Mich., a corporation of Michigan

Application September 13, 1946, Serial No. 696,945

2 Claims. (Cl. 323—123)

1

This invention relates generally to electrical control systems and more particularly to an adjustable phase-shifting system. Objects of this invention are to provide a simplified phase-shifting system of the character described; to provide a system in which the phase of the output of voltage with respect to that of the input of voltage may be adjusted by a single control element; to provide such a system in which the single control element is a common potentiometer resistor; to provide in such a single-control phase-shifting system means whereby the limit of phase shift of the output voltage with respect to the input voltage may be selectively adjusted, and to generally improve phase-shifting systems of the character described.

With the above, as well as other more detailed objects in view which will appear from the following description and the appended claims, there is shown in the drawing a preferred but illustrative embodiment of the invention.

In the drawing which is to be taken as a part of this specification there is illustrated diagrammatically a control system embodying the invention.

A phase-shifting control system designated 1 comprises a transformer T1, a dephasing element or condenser C1, a phase-adjusting element or a potentiometer R1 and a pair of adjustable phase-shift angle-limiting resistors R2 and R3. The transformer T1 has a single iron core 2, a pair of secondary windings 4 and 6, and a center tapped winding providing a pair of primary input windings 8 and 10. The common terminal of the windings 8 and 10 is connected by means of a conductor 12 to one line switch LS1 of a suitable source of alternating current supply. The free terminals of the primary windings 8 and 10 are connected respectively to variable resistors R2 and R3. The opposite terminal of the resistor R2 is connected through the condenser C1 to one end terminal of the potentiometer resistor R1. The other end terminal of the potentiometer resistor R1 is connected to the terminal of the variable resistor R3 opposite to that to which the winding 10 is connected. A conductor 14 connects the adjustable control or wiper element 15 of the potentiometer resistor R1 to the other line switch LS2 of the alternating current source. If desired, a resistor R4 may be connected in shunt with the end terminals of the resistor R1 for stabilizing purposes.

It is thought that the remaining details of the system may best be understood with reference to a description of the operation thereof.

Assuming that the line switches LS1 and LS2

2

are in closed circuit position an alternating current potential will be supplied to the system 1 by the conductors 12 and 14 placing a potential across the capacitive circuit 16 comprising the winding 8, resistor R2, condenser C1 and left-hand portion of the potentiometer resistor R1 and the other or inductive circuit 18 comprising the winding 10, the resistor R3 and the right-hand portion of the potentiometer resistor R1.

10 The value of the capacitor C1 is so chosen with respect to the impedance of the winding 8 that the current through the capacitive circuit 16 will lead the voltage by an angle dependent upon the relative resistive and capacitive reactance of this circuit. 15 The current through the inductive circuit 18 will lag the voltage by an angle determined by the relative proportion of the resistive and inductive reactance of this circuit. The currents flowing through the windings 8 and 10, 20 therefore, will have an angle therebetween which is equal to the sum of the angles of lead and lag of the current in the two circuits 16 and 18. Since the windings 8 and 10 are wound in opposite directions with respect to each other when they 25 are considered in their present parallelly connected relation, when the current in winding 8 is leading the current in the winding 10 by exactly 180° the two currents will be additive in producing a flux in the core 2 and the voltage output of the windings 4 and 6 will be 90° out of phase with the voltage across the conductors 12 and 14.

If the adjustable arm of the potentiometer resistor R1 is adjusted so that substantially all of the resistance of the resistor R1 is placed in the circuit 18, substantially no current will flow through the winding 10 and the flux induced in the core 2 of the transformer T1 will be substantially that due to the winding 8 by a current flowing therethrough which leads the voltage of the conductors 12 and 14. If the resistor R2 is set for zero resistance, the output voltage of the secondary windings 4 and 6 of the transformer T1, assuming them to be properly polarized, will be substantially in phase with the voltage of the conductors 12 and 14. 40 If now the resistor R2 is adjusted upwardly in value, the voltage induced in the secondary windings 4 and 6 will become lagging by an angle proportional to the relative value of the resistance and capacitance of the circuit.

50 If the movable arm of the potentiometer resistor R1 is adjusted so that all of its resistance is in series circuit with the circuit 16, substantially the entire flux induced in the core 2 of the transformer T1 is due to the current flowing through the primary winding 10 which because

of its inductive character will lag the voltage applied between the lines 12 and 14. If the adjustment of the variable resistor R3 is at zero value and substantially no resistance appears in this circuit, then the voltage induced in the secondary windings 4 and 6 of the transformer T1, assuming the same polarization of the windings 4 and 6 as before will lag the voltage applied by the conductors 12 and 14 by substantially 180°. As the value of the resistance of R3 is increased, this angle of lag of the voltage will be decreased in proportion to the ratio of resistance to inductance in this circuit.

If the movable arm of the potentiometer resistor R1 is set at an intermediate point, current will flow through both of the primary windings 8 and 10 of the transformer T1 which will cause flux to be induced in the core 2 of the transformer T1 which is proportional to the vector difference of the currents in the windings 8 and 10. Therefore, at intermediate adjustable points of the potentiometer resistor R1 the voltages induced in the secondary windings 4 and 6 will be somewhere between an in-phase condition and an 180° lagging condition with respect to the voltage of the conductors 12 and 14 depending upon whether the circuit is predominantly inductive or capacitive in nature.

It may now be seen that the system of the invention utilizes a minimum number of control elements and is simple in manufacture and operation. A single, simple control element, such as a potentiometer resistor, is used to shift an output voltage of the system between predetermined limits, these limits being predetermined by adjustable resistors.

What is claimed and is desired to be secured by United States Letters Patent is as follows:

1. The combination of alternating current supply terminals, a transformer having a primary winding and a plurality of secondary windings, each of said windings having a pair of terminals, said primary winding having a terminal intermediate its said pair of terminals, a pair of elements connected in series between said

pair of primary terminals, one of said elements being reactive for producing a dephased current in said primary winding, means for adjusting the magnitude of said dephased current and positioned in series circuit with and intermediate said elements, and circuit means connecting one of said supply terminals to said intermediate terminal and the other of said supply terminals to said adjusting means, each said pair of secondary terminals being adapted to be connected to separate means wherein isolated voltages phased as desired with respect to that of said supply terminals is provided.

2. The combination of alternating current supply terminals, a transformer having a primary winding and a secondary winding, each of said windings having a pair of terminals, said primary winding having a terminal intermediate its said pair of terminals, a pair of elements connected in series between said pair of primary terminals, one of said elements being reactive for producing a dephased current in said primary winding, means for adjusting the magnitude of said dephased current and positioned in series circuit with and intermediate said elements, and circuit means connecting one of said supply terminals to said intermediate terminal and the other of said supply terminals to said adjusting means, said pair of secondary terminals being adapted to be connected to means wherein a voltage phased as desired with respect to that of said supply terminals is provided.
